UNITED STATES PATENT OFFICE.

GUILFORD S. MORLEY, OF UNIVERSITY CITY, MISSOURI, ASSIGNOR TO MAJESTIC MANUFACTURING COMPANY, OF ST. LOUIS, MISSOURI, A CORPORATION OF MISSOURI.

BURNER.

Application filed December 2, 1927. Serial No. 237,205.

This invention relates to burners, and is illustrated herein as embodied in a gas burner of a type similar to that illustrated in United States Letters Patent No. 1,626,047, granted 5 April 26, 1927, in the name of the present applicant, and assigned to the assignee of the present invention.

A burner of the type set forth in the Letters Patent referred to comprises a plurality of 10 concentrically arranged rings, or chambers, into which there is introduced an admixture of gas and primary air. The rings provided with a number of jets, and with openings for conducting secondary air into the center of 15 flames burning at the various jets. To the end of obtaining a proper mixture of the secondary air with the admixture in the burner, each jet is composed of a plurality of flame ports surrounding a central opening for admitting secondary air, and the ports are inclined in such a manner that the flame is concentrated at a point above the central air opening.

With the foregoing considerations in view, 25 the present invention has for an important object thereof the provision of an improved burner which will operate to secure a more thorough mixture of secondary air with a gaseous admixture flowing from jets formed within the burner.

30 A feature of the invention which aims towards the accomplishment of the recited object consists in forming a restriction in each of the central air openings, by means of which the passage of air through the opening and into the flame located thereabove will be accelerated. In the illustrative embodiment of the invention, the restriction is formed intermediate between the ends of each of the central air openings, and is of the same general formation as the restriction within a Venturi tube.

Another object of the invention consists in 35 providing a novel burner of the character specified constructed in such a manner that the flames burning at the various jets will be of a substantially uniform intensity. A feature of the invention which lends itself to the attainment of this object consists in constructing each of the various burner rings in such a manner that the cross-sectional area of the ring tapers from the point at which gas is admitted to the ring, in a decreasing manner, to the closed end of the ring.

Other features and objects of the invention 55 will become apparent from a reading of the following specification in the light of the accompanying drawings, in which—

Fig. 1 is a plan view of a burner embodying the invention;

Fig. 2 is a sectional view in front elevation taken along the line 2—2 of Fig. 1;

Fig. 3 is a view similar to Fig. 2 taken along the line 3—3 of Fig. 1; and

Fig. 4 is a perspective view showing the 65 burner having a cover plate mounted thereon.

As shown in the drawings, the reference numeral 10 indicates the outer ring, or chamber, of a gas burner and 12 the inner ring, or chamber, of the burner. Gas which has previously 70 been mixed with a supply of primary air is admitted to the outer ring 10 through a feed pipe 14, and to the inner ring 12 through a similar feed pipe 16. It is to be observed that the interior of the ring 10 is provided with a 75 solid wall 18 (Fig. 1), and that the outer ring is not in any way in communication with the inner ring, each of the rings being provided with separate feed pipes and separate jets for burning gas admitted through the pipes. 80

It will be observed from an inspection of Figs. 1, 2 and 3 that, upon gas being admitted to the outer ring, it will tend to flow out of the burner through the first jet it reaches, and thus it will be appreciated that by the time 85 the gas has passed completely through the outer ring to come up against the wall 18, the pressure of the gas will be substantially diminished, whereby the flames burning at the last jet in the series will not be of nearly 90 so great an intensity as the flame burning at the first of the jets. To the end of preventing this unequal burning action, and to render substantially uniform the intensities of all 95 of the flames, the outer ring is constructed in such a manner that it tapers from a substantially large cross-sectional area adjacent to the end of the feed pipe 14 to a small cross-sectional area adjacent to the end wall 18. By means of such a provision the gas entering 100 the outer ring will escape partially through each of the jets beneath which it flows, but the pressure within the entire ring will be maintained substantially constant, inasmuch as the cross-sectional area decreases as the 105 gas flows on, whereby the decrease in volume of the gas is accompanied by a proportionate decrease in the cross-sectional area of the

ring. Similarly, the cross-sectional area, or the height, of the inner ring 12 may be decreased in a direction away from the point at which gas is admitted to the inner ring, to accomplish the same result that is accomplished in the outer ring.

As illustrated, the gas jets are each composed of a plurality of burner ports 20 spaced at equal intervals about a central opening 22.

- 10 The position of the burner ports with relation to the central opening is best shown in Fig. 2 of the drawings, and from an inspection of that figure it will be seen that each of the air openings 22 is provided with a 15 restricted portion 24 located intermediately between the ends of the opening. As will also be seen from that figure, the flame ports are inclined in such a manner that flames burning at each of the ports are directed toward a common point located above the center of the air opening.

In the operation of the device, an admixture of gas and primary air is admitted to the inner and outer rings of the burner, from 25 which it passes through the flame ports 20 of the gas jets and burns immediately above the central air openings 22. The flame, in so burning, tends to create a vacuum just above the central air openings, and this tendency 30 draws air forcibly through the openings, whereupon it is mixed with the admixture flowing through the flame ports 20 to insure thorough and complete combustion of the gas. The restriction 24 formed in each 35 of the central openings concentrates the air and accelerates its passage through the opening, thereby increasing the air which is supplied to the flames.

As shown in Fig. 4, a cover plate may be 40 employed in connection with the improved burner. A suitable type of cover plate comprises, as illustrated, a top portion 26 having an opening located above each of the burner jets, and a downwardly extending flange 28 adapted to be spaced from the outer wall 45 of the burner by means of lugs 30. In the operation of the burner, when a cover plate is mounted thereon, secondary air is admitted not only through the central air opening, but

also through the annular opening formed 50 between the outer wall of the burner and the flange 28, and through the annular opening between the burner rings. This supplemental secondary air surrounds the outside 55 of the flame and tends further to secure complete combustion of the gas.

While the invention has been disclosed herein as embodied in a particular type of gas burner, it is to be understood that the invention contemplates being embodied in 60 burners of different types, as well as in burners adapted to burn different fuel.

Having thus described the invention, what I claim as new and desire to secure by Letters Patent of the United States is:

65 1. A gas burner comprising a plurality of gas chambers, gas inlets communicating with the chambers, air passageways extending through the chambers and formed with restrictions between the opposite ends of 70 the passageways to accelerate the passage of air therethrough, and flame ports located adjacent to the air passageways, the gas chambers being of gradually decreasing cross-sectional areas in a direction away from the gas 75 inlets whereby the pressure of gas at various points within the burner remains substantially uniform.

80 2. A burner comprising a gas chamber of gradually decreasing cross-sectional area and having a plurality of air openings formed therein, flame ports surrounding the air openings, restrictions located intermediately between the lengths of the openings to accelerate the passage of secondary air to the interior of the flames during the operation of the burner, and a cover plate adapted to be supported in spaced relation to the burner, the cover plate being provided with openings which register with the air openings when the 85 cover plate is properly positioned with relation to the burner, and the cover plate forming with the burner a conduit for the admission of tertiary air to the flame ports.

85 In testimony that I claim the foregoing 90 I hereunto affix my signature.

GUILFORD S. MORLEY.
